ELECTRICAL CONTROL SYSTEM

William G. Wamsley, Detroit, Mich.

Application June 14, 1946, Serial No. 676,652

10 Claims. (Cl. 318—445)

1
This invention relates generally to electrical control systems which are adapted, among other uses, for controlling multi-speed hoists, elevators and the like.

Primary objects of this invention are to provide a novel control system for a raising and lowering mechanism; to provide a system for controlling a raising and lowering mechanism which provides for one or more automatically controlled steps of acceleration and deceleration; to provide a system having control means operable during a pre-determined travel portion of the mechanism to render the mechanism ineffective to operate at high speed; to provide means whereby when the mechanism approaches its limit of travel its speed is automatically changed to slow speed before reaching the stop position; to provide such a system utilizing energy storage apparatus, preferably condensers, which co-operate in an improved manner with other elements of the system to control change in speed; and to provide a system which is simple to construct and operate. Other objects will be apparent from the specification and the appended claims.

In the drawing, the sole figure shows a schematically arranged wiring diagram for controlling a hoist.

Electrical energy from a suitable source of supply and of suitable voltage is supplied by lines L₁ and L₂ and is controlled by the usual line switches LS₁ and LS₂. A manual pushbutton-control station generally designated MS is suitably positioned so that the operator of the hoist, by pressing either the up button UB or the down button DB or releasing both buttons, causes the hoist to move upwardly or downwardly. Initial inward movement of the button UB closes contacts UP₂ for operating the hoist in an up direction at slow speed. Continued inward movement of the button UB opens contacts UP₁, which causes the hoist to operate in an up direction at high speed. Similarly the button DB acts to close contacts DN₂ and open contacts DN₁ to cause the hoist to operate in a down direction at slow and then high speeds respectively. Release of both buttons UB and DB causes the hoist to stop. Even though the hoist operator may immediately push either of the buttons UB and DB into high speed operation, such manual control of switch MS will not act to immediately complete high speed operating connection for the hoist motor, such completion being delayed for a predetermined time interval by an accelerating control circuit I.

Manual switch MS comprises contacts UP₁ and UP₂ which are closed by bridging bars 18 and

2
18 respectively and which bars are electrically connected together as by a conductor 19. The bars 16 and 18 are apertured and are loosely carried on a push rod 20 extending through the apertures. A spring 21 is positioned around the rod 20 intermediate the bars 16 and 18 and acts to urge the bars 16 and 18 in a parting direction. The rod 20 has spaced pins 22 and 23 therealong which limit movement of the bars 16 and 18 by the spring 21 and are so spaced that when the button UB and rod 20 are held in the position shown, as by spring 24, the bar 18 will be in engagement with pin 23 and held thereby out of engagement with contacts UP₂. When the bar 16 is held in circuit-making position against the contacts UP₁, the pin 22 is spaced outwardly from the bar 16 so that upon inward movement of the button UB, pin 23 will have permitted the bar 18 to engage the contacts UP₂ for completing an electric circuit therebetween prior to the engagement of pin 22 with bar 16 so that at a partially inward position of button UP, both sets of contacts UP₁ and UP₂ will be in circuit-making position. Further inward movement of the button UB will cause pin 22 to engage bar 16 and open contacts UP₁. Similarly the down button DB has a rod 25, a spring 26 urging button UB outwardly, a spring 27 urging bridging bars 28 and 29 connected by a conductor 30 in a parting direction, and pins 31 and 32, so that upon inward movement of the button DB, bar 29 closes the circuit between contacts DN₂, and subsequently bar 28 opens the circuit between contacts DN₁.

The circuit I includes an accelerating relay 35 having one terminal of its coil AR directly connected to the line L₁ and its other terminal connected through the contacts UP₁ and DN₁ to the line L₂. A timing condenser AC controls the interval between the initiation of actual high speed 40 operation and the time the operator sets the button UB or DB for such operation. This condenser AC is connected across the terminals of the relay coil AR and is normally maintained fully charged by normally closed circuit I. Upon de-energization of the accelerating relay circuit I due to manual movement of buttons UB or DB to high speed position, the condenser AC discharges through and maintains the accelerating relay coil AR energized for a predetermined time interval 45 after de-energization of the accelerating relay circuit I so that even if the buttons UB or DB are instantaneously moved from stop position to high-speed position, the low speed connection for the hoist will be maintained for a predetermined time interval.

A low speed control circuit 2 is connected between the lines L1 and L2 and energizes the low-speed relay having the coil LR. Starting from line L1, this circuit 2 includes parallelly arranged, normally open contacts AS1 of the accelerating relay and normally closed contacts HS1 of the high-speed relay, relay coil HR, and parallelly arranged branch circuits connected to the line L2. One of these branch circuits includes normally open contacts DS1 of a decelerating relay having a coil DR. Another of the branch circuits includes normally open contacts US2 of an up-relay having a coil UR and contacts UP2 of switch MS. Another of the branch circuits includes normally open contacts DNS2 of a down-relay having a coil DNR and contacts DN2 of switch MS.

A circuit 3 is arranged to actuate the up-relay coil UR so that upon energization of the low-speed relay coil LR or the high-speed relay coil HR, the motor 12 will operate in the direction to raise the hoist at either slow or high speed. The circuit 3 starting from line L1 includes the normally closed contacts ULS1 of the up-limit switch ULS, relay coil UR of the up-relay, and normally open contacts UP2 directly connected to line L2. Circuit 3 also has a branch circuit extending from a point intermediate coil UR and contacts UP2 which includes contacts US2 of the up-relay and holding contacts DS1 of the decelerating relay.

A high-speed control circuit 4 controls the energization of the coil HR of the high-speed controlling relay and, when energized, operates the motor 12 at high speed in a direction depending upon whether the up-relay coil UR or the down-relay coil DR is energized. Circuit 4 extends from the line L1 through normally closed contacts AS2 of the accelerating relay, coil HR, selector switch contacts SSU, contacts ULS2 of the up-limit switch ULS, contacts DNS1 of the decelerating relay, the holding contacts US2 of the up-relay, and contacts UP2 to line L2. A branch circuit extends from a point intermediate the coil HR and contacts SSU through contacts DLS2 of the down-limit switch and through contacts SSD of the selector switch SS to a point intermediate the contacts SSU and ULS2, so that when the selector switch SS is in its up position closing contacts SSU, it is immaterial, in so far as operation in an up direction of the high-speed circuit 4 is concerned, whether the contacts DLS2 are open or are closed. When the selector switch SS is in its down position, opening the contacts SSU and closing contacts SSD, the contacts DLS2 also control the energization of circuit 4 so that when the hoist is adjacent its low limit and contacts DLS2 are held open by the down-limit switch DLS, the hoist is rendered ineffective to operate at high speed until the hoist has moved upwardly enough to allow the contacts DLS2 to be closed by the down-limit switch DLS. A second branch circuit extends from the contacts DLS2 through normally closed contacts US1 of the up-relay in parallel relation with contacts SSD, ULS2, and DNS1.

A decelerating control circuit 5 extends from line L1 through the normally open contacts HS2 of the high-speed relay, the relay coil DR of the decelerating relay, and then branches into branch circuits to line L2. One of these branch circuits includes the contacts US2 of the up-relay and the contacts UP2 of the switch MS. Another of the branch circuits includes the contacts DNS2 of the down-relay and the contacts DN2 of the switch

MS. A third branch or holding circuit includes the holding contacts DS1 of the decelerating relay which are directly connected to line L2. A timing condenser DRC has its terminals connected directly across the end terminals of the relay coil DR and acts in a manner similar to the timing condenser AC to maintain the relay coil DR energized for a predetermined time interval after the circuit 5 has been de-energized.

10 A down direction control circuit 6 extends from line L1 through the normally closed contacts DLS1 of the down limit switch DLS, the relay coil DNR of the down relay, and contacts DN2 of switch MS to line L2. The circuit 6 also includes 15 a branch holding circuit through contacts DNS2 of the down-relay and contacts DS1 to line L2.

Energization of the relay coils UR or DR closes contacts US3 and US4 and DNS3 and DNS4 respectively for rendering an electrical 20 power circuit 8 in condition to operate an electric motor 12 in a hoist-raising or hoist-lowering direction. Energization of the relay coils LR or HR closes contacts LS1 or HS3 and HS4 respectively to cause the motor 12 to operate at either 25 a low or a high rate of speed. In the instance shown, circuit 8 is arranged to operate the direct current motor 12. The particular power circuit which is used is immaterial, as the motor circuit per se does not form a part of this invention, and 30 it will be obvious to one skilled in the art that an alternating current motor and power circuit could be used. Motor 12 operates upon energization of one of the relay coils UR or DNR and one of the relay coils LR or HR to rotate the cable drum 35 14 to raise or lower the hoist (not shown).

Worm gears 33 and 34 are driven through suitable gearing 35 by the cable drum 14. A down-limit switch actuating cam 36 is driven by the worm gear 33 and an up limit switch actuating cam 37 is driven by the worm gear 34 for actuating the down and up limit switch DLS and ULS respectively. Upon rotation of the cam 36, the down-limit switch DLS will ride upwardly on the cam finger 38 raising the down-limit switch 40 push rod 39 and opening the contacts DLS2. The contacts DLS1 will remain closed because of the lost motion between the rod 39 and the loosely fitting bar 40 bridging the contacts DLS1. Bar 40 therefore will not be disengaged from contacts 45 DLS1 until the rod 39 has been moved by cam finger 38 further in an upward direction causing pin 41 carried by rod 39 to engage and move the bar 40 out of circuit-making engagement.

The up-limit switch ULS is similarly constructed and its rod 42 is similarly actuated by cam finger 43 to cause pin 45 to move bar 44 out of circuit making relation with the contacts ULS1 subsequent to the opening of the circuit through contacts ULS2.

60 The operation of the control circuit is as follows: Closure of the line switches LS1 and LS2 energizes the line conductors L1 and L2 respectively, which will immediately energize the accelerating relay coil AR and its associated timing condenser AC due to the closed condition of the contact members UP1 and DN1. With the manual switch MS in the position shown, this is the only result of the closing of the line switches LS1 and LS2. If now it is desired to cause the 65 cable drum 14 to be rotated in a direction to raise the hoist, the up button UB is manually pressed inwardly to close the normally open contacts UP2 which complete the circuit 3 energizing the up relay coil UR. Energization of the coil UR opens the normally closed contacts US1 and closes the 70 75

normally open contacts **US2** to complete a circuit from the line **L1** through now closed contact members **AS1**, relay coil **LR**, and now closed contact members **US2** and **UP2** to line **L2**. Energization of the relay coil **LR** closes the contact members **LS1** which, together with the closure of the contact members **US3** and **US4** which were closed by the energization of the up relay coil **UR**, causes the motor **12** to rotate the cable drum **14** at low speed for up movement of the hoist. It will be noted at this time that the pin **22** of the up button **UB** has not as yet engaged the bridging bar **16** of the up button **UB** to open the contact **UP1** and, therefore, as long as the up button **UP** is maintained in this position, the motor **12** will continue to operate to raise the hoist at slow speed. If it is now desired to operate the hoist in an upward direction at a high speed, the up button **UB** is pressed inwardly further to cause the pin **22** to move the bridging bar **16** out of circuit-making position with the contacts **UP1**. This opening of the contacts **UP1** immediately de-energizes the accelerating relay control circuit **1**. However, due to the charged condition of the timing condenser **AC**, the accelerating relay coil **AR** will not immediately be de-energized, but will act as the discharge circuit for the timing relay condenser **AC**. Therefore, until the condenser **AC** is substantially discharged, this coil **AR** will remain energized holding the contacts **AS1** closed and the contacts **AS2** open, and the hoist continues to operate at the slow speed in an upward direction. Subsequent to the discharge of the timing condenser **AC**, the coil **AR** will be de-energized, opening the contacts **AS1** and closing the contacts **AS2**. Opening of the contacts **AS1** causes no change in the operation of the motor **12**, since a parallel circuit around the contacts **AS1** through the normally closed contacts **HS1** is maintained. Closure of the contact **AS2**, however, acts to energize the relay coil **HR** by closing the circuit **4** which extends from the line **L1** through the contacts **AS2**, the relay coil **HR**, the now-closed contacts **SSU**, the now closed contacts **ULS2**, the closed contacts **DNS1**, the closed contacts **US2**, and closed contacts **UP2** to the line **L2**. Energization of the coil **HR** immediately opens the normally closed contacts **HS1** to de-energize the low-speed relay coil **LR**. Energization of the high-speed relay coil **HR** also closes the contacts **HS3** and **HS4** which, with the opening of the contacts **LS1**, due to de-energization of the low-speed relay coil **LR**, will place the motor **12** in a condition to rotate the cable drum **14** in a direction for raising the hoist at a high rate of speed. Energization of the coil **HR** also closes contacts **HS2**, completing the decelerating control circuit **5**, contacts **US2** and **UP2** having been previously closed as hereinbefore described, to energize coil **DR** and close contacts **DS1**, completing a holding circuit in to line **L2** in parallel with contacts **US2** and **UP2**. Energization of circuit **5** also causes the condenser **DRC** to become charged. Assuming that the operator wishes the hoist to be raised to its uppermost position, he manually maintains the up button **UB** in the present innermost position with contacts **UP2** closed and contacts **UP1** open. As the cable drum **14** rotates it acts through the gearing **35** to rotate the worm gear **34** until the up-limit switch actuating cam **37** rotates so that the cam finger or lobe **45** thereof moves the up limit switch actuating rod **42** which will first open the contacts **ULS2**, but due to the lost-motion connection between the pin **43** and the bridg-

ing bar **44**, the contacts **ULS1** will remain closed. Opening of the contacts **ULS2** de-energizes the aforementioned circuit **4**, including the high-speed relay coil **HR**, so that the contacts **HS3** and **HS4** will open and the contacts **HS1** will close. Closure of the contacts **HS1** immediately energizes the circuit **2** and the included low-speed relay coil **LR** through closed contacts **US2** and **UP2**. The parallel branch circuit through now-closed contacts **DS1** will remain completed for a predetermined time interval subsequent to de-energization of circuit **5** because of the now-charged condenser **DRC** which discharges through coil **DR** to maintain it energized for a predetermined time interval. If, as is the case here, the contacts **UP2** are maintained closed, this discharge of condenser **DRC** is without effect as far as continued low-speed operation is concerned.

Energization of the coil **LR** re-establishes a closed circuit through the contacts **LS1** and places the motor circuit in condition to operate the motor **12** and cable drum **14** at a low speed in an upward direction of the hoist. Continued upward movement of the hoist **14** will cause the up-limit switch actuating cam lobe **45** to continue the upward movement of the up-limit switch bar **42** to take up the lost motion between the pin **43** and the bridging bar **44** to open contacts **ULS1** to de-energize the circuit **3** and the up-relay coil **UR**. De-energization of the coil **UR** opens the contacts **US2**, **US3**, and **US4** and closes the contacts **US1**. Opening of the contacts **US2** de-energizes the circuit **2** and the low-speed relay coil **LR**, opening the contacts **LS1**, the branch circuit through contacts **DS1** having been previously de-energized as above described. The opening of the contacts **LS1**, **US3**, and **US4**, as heretofore described, de-energizes the circuit for the motor **12**, and rotation of the cable drum will stop.

If now, instead of maintaining the up button **UB** depressed in the normal high-speed operation of the hoist, the operator had desired to reduce the speed of the hoist at an intermediate position, he would have released the pressure on the up button **UB** until the bridging bar **16** moved upwardly to close the contacts **UP1**. Closure of the contacts **UP1** energizes circuit **1** and the relay coil **AR**. Energization of coil **AR** acts to close the contacts **AS1** and open contacts **AS2**. Opening of the contacts **AS2** de-energizes circuit **4** and the high-speed relay coil **1** to open the contacts **HS2**, **HS3**, and **HS4**, and to close the contacts **HS1**. Closure of the contacts **HS1** energizes the control circuit **2** and the coil **LR** of the low-speed relay, closing the contacts **LS1** to place the circuit for the motor **12** in condition to operate the drum **14** in the clockwise or up direction of the hoist at slow speed. If, after operating the hoist at low speed in an up direction as described, the operator desires to stop the same, he releases the up button **UB**, allowing the circuit **2** through contacts **UP2** to open to de-energize the low-speed relay coil **LR** and to de-energize the circuit **3** of the relay coil **UR** whereby the contacts **US2** are opened. Contacts **LS1**, **US3**, and **US4** will be opened and the circuit for the motor **12** de-energized to stop rotation of the cable drum **14**.

If, when the hoist was being operated in an upward direction at high speed the operator immediately released all pressure on the up button **UB**, the contacts **UP2** would be opened and the contacts **UP1** would be closed. Closure of the contacts **UP1** energizes the circuit **1** and its relay coil **AR** to close the contacts **AS1** of the low-

speed control circuit 2 and to open the contacts AS2 of the high-speed control circuit 4. As will be presently explained, contacts DS1 will remain closed for a predetermined timing interval to maintain relay UR energized. Consequently, closure of contacts AS1 will energize the low-speed control circuit 2 to energize coil LR for closure of contacts LS1 to place the circuit for the motor 12 in condition to operate motor 12 and drum 14 at low speed in the up direction. Opening of the high-speed control circuit 4 de-energizes the high-speed control relay winding HR which, as hereinbefore set forth, opens the contacts HS2, HS3, and HS4 and closes contacts HS1. Opening of contacts HS3 and HS4 de-energizes the high-speed portion of the circuit for motor 12. Closure of contacts HS1 energizes the by-pass or parallel circuit around the now closed contacts AS1 without effect. Opening of the contacts HS2 de-energizes the decelerating control circuit 5, but the deceleration control relay will not, however, immediately be de-energized because of the timing condenser DRC which discharges through the relay coil DR and maintains, for a predetermined time interval, the contacts DS2 and DS1 in closed circuit position maintaining the branch circuits of low-speed and up direction control circuits 2 and 3 energized, even though, at the time, the up button UB was fully released, and the branch circuits thereof, through contacts UP2, were opened. After a predetermined time interval the condenser DRC will have discharged, and coil DR will be de-energized, so that the contact DS1 will open to de-energize the low speed and up direction control circuits 2 and 3, including coils LR and UR. De-energization of coil LR causes the low-speed relay to open the contacts LS1, and de-energization of coil UR causes the up relay to open contacts US3 and US4. Opening of contacts LS1, US3, and US4 de-energizes the control circuit for motor 12 and stops rotation of the cable drum 14.

When the hoist is being started in the upward direction from a point at or adjacent the low limit of its travel and the selector switch SS is arranged in the down position so that it closes the contacts SSD, the circuit 4 of the high-speed relay coil HR is now caused to be controlled by the contacts DLS2 of the down-limit switch. As set forth hereinbefore, when the cable drum 14 is in a position in which the hoist is at or adjacent its low limit, the operating rod 39 will be held in a raised position by the cam lobe 38 until the drum 14 has caused the hoist to be moved a predetermined distance from the bottom limit of its travel. As was explained hereinbefore, this raised position of rod 39 will maintain contacts DLS2 open. Therefore, if the hoist is operating within this limit with the lobe 38 of the down-limit switch actuating cam 36 holding the contacts DLS2 open, energization of the high-speed relay coil HR is prevented. This prevents energization of coil HR and allows the normally closed contacts HS1 to remain in closed circuit position so that the relay coil LR of the low-speed relay may be energized and control the operation of the motor 12. Unless coil HR is energized contacts HS3 and HS4 remain open. When, however, the selector switch SS is in an up position, as shown, closing the contacts SSD, the condition of the contacts DLS2 is immaterial and will not affect the operation of the hoist at either low speed or high speed in an upward direction.

Manual operation of the DB button of the manual switch MS acts to close contacts DN2,

and continued downward movement of the DB button acts to open the contacts DN1 to control the operation of the motor 12 and cable drum 14 in much the same manner as the up button UB, but in the opposite direction. In this case closure of the contacts DN2 energizes the down direction control circuit 6 from the line L1 to the closed contacts DLS1, the relay coil DNR of the down direction relay through the now closed contacts DN2 to the line L2. Energization of the relay coil DNR will close the contacts DNS2 of the relay coil DNR, closing the circuit 2 through the low-speed relay coil LR from the line L1 through the now-closed contacts AS1, the relay coil LR, contacts DNS2, and through the now-closed contacts DN2 to the line L2. Energization of the relay coil LR causes the contacts LS1 to be closed, and energization of the relay coil DNR causes the contacts DNS3 and DNS4 to be closed for controlling the circuit for the motor 12, so that the motor 12 and the cable 14 are operated in a direction for lowering of the hoist at a slow speed.

If now the down button DB is pressed inwardly still further so that the pin 31 engages the bridging bar 28 and forces it downwardly to open the contacts DN1, the accelerating control circuit 4 will be de-energized, and, as heretofore stated, after the timing condenser AC has discharged through the relay coil AR, the contacts AS1 will be opened and the contacts AS2 will be closed. Closure of the contacts AS2 closes the circuit 4 through the high-speed relay coil HR from the line L1 through the now-closed contacts AS2, the relay coil HR, the now-closed contacts DLS2, US1, DNS2, and DN2 to the line L2. If the down button DB is maintained in this position, as the hoist reaches its low position the worm 33 driven through gearing 35 by the cable drum 14 will rotate the down limit switch actuating cam 36 so that its lobe 38 engages the operating rod 39 of the down-limit switch DLS to open the contacts DLS2 which de-energizes the circuit 4 through the high-speed relay coil HR, causing the low-speed operating circuit 2 of the motor 12 to be energized in a manner similarly to that set forth hereinbefore. Continued rotation of the cable drum 14 in a direction to lower the hoist causes cam lobe 38 to take up the lost motion between pin 41 and bar 40 to open the down direction control circuit 6 to open contacts DNS2 which de-energizes the low-speed control circuit 2. De-energization of the circuits 2 and 6 opens contacts LS1, DNS3, and DNS4 to stop the motor 12 and drum 14.

Immediate release of the down button DB prior to the hoist reaching the down end of its travel and prior to being operated by the down-limit switch acts to place the motor 12 at its low-speed operating condition until discharge of the timing condenser DRC through the relay coil DR, at which time the contacts DS1 are opened to de-energize the low-speed relay coil LR, causing the motor 12 to be de-energized and stop. Release of the down button DB sufficient to close contacts DN1 and maintain contacts DN2 closed, de-energizes the high-speed control circuit 4 due to the energization of circuit 4 and coil AR and energizes the low-speed control circuit 2 to open contacts HS3 and HS4 and to close contacts LS1 for placing the circuit 8 of motor 12 in condition to operate the motor in the down direction at low speed. Subsequent release of the button DB opens contacts DN2 to de-energize circuits 2 and

6 causing contacts LS1, DNS3, and DNS4 to open to stop the motor 12.

As described above, the timing condenser AC and control relay AR become energized immediately upon closure of the line switches LS1 and LS2, in readiness for starting operation in either the raising or lowering direction. Under some conditions, it may be desirable to delay the initial energization of condenser AC and relay AR until the starting button UB or DB, as the case may be, is actuated to either a high speed or a low speed running position. Such operation may be effected by moving the indicated transfer switch T from its full line position, to a position in which it is disconnected from terminal 51, and is connected to terminal 52. Terminal 52 is connected to a conductor 53 which in turn is connected to line L2 through the previously described control relay contact DS1. Under the conditions now being described, when button UB, for example, is moved from the off position to the low speed position, such action connects circuit 1 to line 1, through contacts UP1, conductor 19 and contacts UP2, which action immediately energizes relay AR and condenser AC. Even if button UB is quickly moved from the off position to the full speed position, there is a short interval, as above described, during which both contacts UP1 and UP2 become energized, which interval is long enough to fully charge condenser AC and cause relay AR to assume the energized position. Similar comments apply to an operation of button DB to either the low speed or the high speed position.

Similarly, when the button UB or DB is moved from the running position to the off position, there is a short interval during which both of the corresponding contacts UP1 and UP2, or DN1 and DN2, are closed, during which interval condenser AC and relay AR are, respectively, recharged and re-energized. To positively insure such a recharging and re-energizing, the connection through conductor 53 and contacts DS1, afford a positive re-energizing and recharging circuit for relay AR and condenser AC, under decelerating conditions.

This invention provides a simple control arrangement whereby a hoist, irrespective of the operator, must always be started at low speed and cannot be immediately brought to high speed in a manner which might damage the work being transported or cause the hoist cable to be broken but must first be operated for a predetermined time interval through its low speed connections, thereby providing a desirably gradual rate of acceleration of the hoist. The control provides means for selectively rendering the hoist operable at only low speeds adjacent the low end of its range of travel. The circuit also provides means whereby the hoist, whether moving upwardly or downwardly at the time, is not stopped immediately from the high speed operation but must go through a predetermined time period of operation through its low speed connections before it will stop, thus providing a desirably gradual rate of deceleration and preventing damage to the materials being carried by the hoist.

What is claimed and is desired to be secured by United States Letters Patent is as follows:

1. In a multi-speed electric control system, a first circuit operable to control operation of a mechanism at a first speed, a second circuit operable to control operation of said mechanism at a second speed, a first circuit controlling means having two operating positions, said means in one

of said positions being operable to energize said first circuit and in the other of said positions being operable to energize said second circuit, a third circuit for controlling said controlling means, a second circuit controlling means having three positions of operation, said second controlling means being operable in one of said positions to energize said third circuit and in the second of said positions to energize said second circuit and in the third of said positions to de-energize said third circuit.

2. In a multi-speed electric control system, a first electric circuit operable to control operation of a mechanism at a first speed, a second electric circuit operable to control operation of a mechanism at a second speed, a first accelerating relay controlling means having two positions of operation, said means when in one of said positions being operable to energize said first circuit and when in the second of said positions being operable to energize said second circuit, a third electric circuit operable to control said first controlling means, said first controlling means being operable upon energization of said third circuit to move to said one position and upon de-energization to move to said second position, a second up controlling means having three positions of operation, said second means being operable in the first of said positions to energize said third circuit and in the second of said positions to energize said first circuit and maintain said third circuit energized and in the third of said positions to energize said second circuit and to de-energize said third circuit, and time delay means operable upon de-energization of said third circuit to maintain said first controlling means in said one position for a predetermined time interval.

3. In a multi-speed electric control system, a first circuit operable to control the operation of a mechanism at a first speed, a second circuit operable to control the operation of the mechanism at a second speed, a first controlling means having two operation positions, said means being operable in one of said positions to render said first circuit in condition to control said mechanism and in the second of said positions to render said second circuit in condition to control said mechanism, a third electric circuit operable to control said means, a second controlling means having three positions, said second controlling means when in the first of said positions being operable to control said third circuit whereby said first controlling means is placed in its said one position, said second controlling means when in the second of said positions being operable to control said first circuit for operation of said mechanism, said second controlling means when in the third of said positions being operable to control said third circuit whereby said first controlling means is placed in its said second position, and means for delaying the operation of said first controlling means for changing from said one to said second controlling positions until a predetermined time interval has elapsed after said second controlling means has been placed in said third position from said second position.

4. In a multi-speed electric control circuit for an electrically operated motor, a first electric circuit for energizing the motor to operate at a first speed, a second electric circuit for energizing the motor to operate at a second speed, an energizable circuit controlling means operable upon energization to energize said first circuit and operable upon de-energization to energize said

second circuit, a third electric circuit for energizing said circuit controlling means, means operable upon de-energization of said third circuit for maintaining said circuit controlling means energized for a predetermined time interval, and means operable to energize said first circuit and to de-energize said third circuit.

5. In a multi-speed electric control circuit for an electrically operated motor, a first circuit operable to energize the motor for operation at a first speed, a second circuit operable to energize the motor for operation at a second speed, switch means for energizing said first circuit, an energizable accelerating control means, a third circuit for energizing said accelerating means, and time delay means for energizing said accelerating means and operable upon de-energization of said third circuit to maintain said accelerating means energized for a predetermined time interval, said accelerating control means being operable upon de-energization to energize said second circuit.

6. In a multi-speed electric control circuit for an electrically operated motor, a first circuit operable to energize the motor for operation at a first speed, a second circuit operable to energize the motor for operation at a second speed, switch means operable by said motor for de-energizing each of said circuits in predetermined succession, a second switch means for energizing said first circuit, an energizable accelerating control means, a third circuit for energizing said accelerating means, and time delay means for energizing said accelerating means and operable upon de-energization of said third circuit to maintain said accelerating means energized for a predetermined time interval, said accelerating control means being operable upon de-energization to energize said second circuit.

7. In a multi-speed electric control for a hoist, means operating the hoist in one of two directions and operable at a first speed and at a second speed, a first control circuit operable to cause said hoist to travel at said first speed, a second control circuit operable to cause said hoist to travel at said second speed, means for actuating said circuits in sequence so that the hoist will start its movement at said first speed and continue its movement at said second speed, time control means operable to determine the time interval between the time of actuation of said second circuit by said actuating means and the time said second circuit becomes effective to cause the hoist to operate at said second speed, and control means operable to render said second circuit ineffective during movement of said hoist within a predetermined range of movement in one direction.

8. In a multi-speed electric control for a hoist, means operating the hoist in one of two directions and operable at a first speed and at a second speed, a first control circuit operable to cause said hoist to travel at said first speed, a second control circuit operable to cause said hoist to

travel at said second speed, means for actuating said circuits in sequence so that the hoist will start its movement at said first speed and continue its movement at said second speed, time control means operable to determine the time interval between the time of actuation of said second circuit by said actuating means and the time said second circuit becomes effective to cause the hoist to operate at said second speed, means operable subsequent to the operation of said time control means to render said first circuit ineffective, and control means operable to render said second circuit ineffective during movement of said hoist within a predetermined range of movement in one direction.

9. In a multi-speed electric control system, a first circuit operable to control the operation of a mechanism at a first speed, a second circuit operable to control the operation of the mechanism at a second speed, circuit controlling means operable to control said circuits in predetermined succession, and means including electric energy storage means operable to determine the time interval between control of one of said circuits and the control of the other of said circuits.

10. In a multi-speed electric control system, a first electric circuit operable to control operation of a mechanism at a first speed, a second electric circuit operable to control operation of a mechanism at a second speed, a first accelerating relay controlling means having two positions of operation, said means when in one of said positions being operable to energize said first circuit and when in the second of said positions being operable to energize said second circuit, a third electric circuit operable to control said first controlling means, said first controlling means being operable upon energization of said third circuit to move to said one position and upon de-energization to move to said second position, a second up controlling means having three positions of operation, said second means being operable in the first of said positions to energize said third circuit and in the second of said positions to energize said first circuit and maintain said third circuit energized and in the third of said positions to energize said second circuit and to de-energize said third circuit, and time delay means including electric-energy storage means operable upon de-energization of said third circuit to maintain said first controlling means in said one position for a predetermined time interval.
